UNITED STATES PATENT OFFICE.

RODNEY G. RICHARDSON, OF CHICAGO, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE-REPEATER.

1,344,210.

Specification of Letters Patent. Patented June 22, 1920.

Application filed August 23, 1916. Serial No. 116,483.

To all whom it may concern:

Be it known that I, RODNEY G. RICHARDSON, a citizen of the United States of America, and a resident of Chicago, county 5 of Cook, and State of Illinois, have invented certain new and useful Improvements in Automatic Telephone-Repeaters, of which the following is a specification.

My invention relates in general to repeaters for automatic telephone systems, and has for its principal object the provision of means in such repeaters for transmitting impulses of uniform length regardless of irregularities in the length of the received 10 impulses.

In modern multi-office automatic systems in which the automatic switches are directly controlled by impulses transmitted from the individual subscribers' calling devices considerable difficulty has been experienced in adjusting the length of impulses delivered by the calling devices so as to insure accurate and rapid operation of the switches in different offices. This difficulty 25 is largely due to differences in the capacity and resistance of the trunks and is accentuated by variations between the individual calling devices themselves.

My improved repeater is adapted to receive a uniform series of short impulses, a uniform series of long impulses, or a series of irregular impulses; and in each case translate the received impulses into a uniform series of standard length impulses, thereby insuring the accurate operation of 30 automatic switches independent within wide limits of the adjustment of the individual calling devices.

The particular means employed in attaining the foregoing ends and the operation thereof will be fully described hereinafter, reference being had to the accompanying drawings, in which Figures 1, 2, and 3, when placed in order with the lines at the ends 40 thereof in alinement, represent diagrammatically a complete circuit connection between a calling substation A and a called substation A' in a system embodying the principles of my invention. The said connection has been established through the medium of the individual line switch C, the selector switch E, the repeater R, the selector switch F, and the connector H. In Fig. 4 I have shown a modified form of the repeater 50 R shown in Fig. 2.

Referring now to Fig. 1, the substation A may be of any approved automatic type, such, for example, as the substation shown in British Patent to Martin, #1419 of 1910. As represented herein, it comprises essentially the receiver 2, transmitter 3, switch hook 4, ringer 5, and condenser 6. Being an automatic substation, there is also provided a pair of impulse springs 7 and 8 controlled by an impulse wheel 9 through the 60 medium of a finger hole dial (not shown).

The line conductors 11 and 12 of the substation A are connected at the exchange to the individual line switch C which is of the general type of line switch disclosed in the 70 British Patent to James #26,301 of 1906; being, however, of the particular type shown in U. S. Letters Patent #1,078,690, granted Jan. 17, 1912, to Frank Newforth. Since line switches of the above description are 75 well known and form no part of my invention they will not be described in detail. It will suffice to say here that through the medium of line switch C the line of substation A when calling is given access to a plurality of trunk lines extending to selector switches.

The line switch C and a plurality of similar line switches are controlled in their trunk selecting operations by means of a 85 master switch D. The master switch D is of the general type of master switch disclosed in the above-mentioned British Patent to James, #26,301 of 1906; being, however, more nearly of the particular type disclosed in the British Patent to Martin, #1419 of 1910, also previously referred to. As is well known, the function of the master switch is to maintain the plungers of all idle 90 line switches which it controls in position 95 before the terminals of an idle trunk line.

One of the trunk lines to which the line switch C has access is shown in Fig. 1 extending to the selector switch E. The selector E may be of the general type of selector switch disclosed in U. S. Letters Patent #815,321, granted March 13, 1906, to Keith, Erickson, and Erickson; being, however, of the particular type disclosed in British Patent to the Automatic Telephone Mfg. Co., #2543 of 1914. A selector switch of the foregoing description, when used in a multi-office system such as contemplated herein, may be operated in response to the first digit of a called number to select one 100 105 110

of the main groups or exchanges into which the subscribers' lines in the system are divided. For this purpose the selector E, in common with other selectors, may be given 5 access to a number of groups of trunk lines, each group of trunk lines extending by way of repeaters to a different exchange.

One of these trunk lines is shown extending from the bank contacts 73, 74, and 10 75 by way of conductors 80, 81, and 82, repeater R (Fig. 2), and trunk line conductors 83 and 84 to the selector F. The repeater R is, of course, introduced into the trunk 15 circuit primarily for the purpose of obviating the necessity of continuing the third conductor, conductor 81, to the distant exchange; but in accordance with my invention this repeater also has another function, that of standardizing the impulses, which 20 will be fully explained hereinafter.

The selector F is similar to the selector E, already described, and is operable in response to the second digit of a called number to select one of the groups into which 25 the lines of the exchange are divided. To this end the selector F, in common with other similar selectors, is given access to a number of groups of trunk lines, each of which groups extends to a group of connector switches which are adapted to complete 30 connections to a group of individual lines.

In Fig. 2 one of these trunk lines is shown extending from the bank contacts 173, 174, 35 and 175 to the connector H (Fig. 3). The connector H may be of the general type of connector switch disclosed in U. S. Letters Patent #815,176, granted March 13, 1906, to Keith, Erickson, and Erickson; being 40 however, of the particular type disclosed in U. S. Letters Patent #13,901, reissued April 13, 1915, to Frank Newforth. A connector switch of the foregoing type may be operated in response to the two last digits of a 45 called number to connect with an individual line in the group to which it has access.

One of the lines accessible to the connector H is the line extending to substation A' which substation, together with its associated line switch C', may be similar to the substation A and line switch C in Fig. 1.

To supply current for operating and talking purposes I have shown the batteries B 55 and B' each having its positive pole grounded. The auxiliary pieces of apparatus associated with the connector H comprising the ringing current generator Gen, the ringing interrupter I, and the busy signaling machine Q are of the ordinary type and perform the same functions as the same named pieces of apparatus in other automatic exchanges.

Having given a brief description of the 60 apparatus, I will now proceed to a descrip-

tion of the operations of the same. For the purposes of this explanation it will be assumed that the subscriber at substation A desires to obtain connection with the subscriber at substation A'. Inasmuch as a 70 great deal of the equipment shown herein is old and well known in the art, having been fully described in the publications previously referred to, the operation of such equipment will be described in a more or 75 less general manner.

Referring to Fig. 1, when the subscriber at substation A removes his receiver to initiate the call, an energizing circuit is completed over the line conductors 11 and 12 80 for the line relay 16 of the line switch C. Upon attracting its armature, the line relay 16 closes a circuit for the pull-in winding 17. Upon energizing, the pull-in winding operates both the plunger arm 21 and the cut-off armature 22; the former through the medium of its plunger (not shown) forcing the bank springs 30-33, inclusive, into engagement, respectively, with contacts 34-37, inclusive; and the latter disconnect- 85 the line conductors 11 and 12, respectively, from ground and from the line relay 16. By the engagement of bank springs 30 and 33, respectively, with contacts 34 and 37, the line conductors 11 and 12 are extended 90 to the double-wound line relay 60 of the selector E.

The line relay 60 is accordingly energized over the loop circuit including substation A and, upon attracting its armature, closes 100 a circuit for the slow-acting release relay 61. Upon energizing in turn, the relay 61 completes a holding circuit for the line switch C which may be traced as follows: Ground at G, contact springs 91, contact 105 35, bank spring 31, and holding winding 18 to battery B. Since the line relay 16 is slow-acting, it retains its armature to maintain the pull-in winding 17 energized until after the above holding circuit has been established. A branch of the holding circuit extends by way of conductor 19 to multiple test contacts in the banks of connector switches having access to the line of substation A where by a ground potential on 110 these test contacts the said line is made busy. By the engagement of bank spring 32 with contact 36 the master switch D is operated in well known manner to advance the plungers of all the remaining idle line 115 switches into position before the terminal of the next idle trunk line.

The foregoing operations whereby the line conductors 11 and 12 have been extended through to the line relay 60 of the 120 selector E have taken place in response to the removal of the receiver at substation A. The calling subscriber may now manipulate his dial in accordance with the first digit of the desired number, thereby separating 130

momentarily the impulse springs 7 and 8 a number of times and interrupting each time the circuit of line relay 60 of selector E. As a result of these interruptions of its circuit the line relay 60 is deenergized a corresponding number of times, sending an impulse at each deenergization from ground at G⁶ to the slow-acting relay 62 and the vertical magnet 65 in series. The vertical magnet in response to these impulses, steps up the switch shaft until the wipers 70, 71, and 72 stand opposite the horizontal level in which are located contacts which are terminals of trunk lines extending to the exchange in which the wanted subscriber is located. The relay 62, being slow-acting, retains its armature during the series of impulses and closes a circuit for the test relay 64, which latter relay prepares a circuit for the rotary magnet 66 and locks itself to ground at G⁷. At the end of the series of impulses the relay 62 deenergizes, thereby completing the aforementioned circuit of the rotary magnet 66, whereupon the wipers 70, 71, and 72 start rotating in search of an idle trunk line. As is well known, the rotary magnet interrupts its own circuit and also the locking circuit of the test relay at every energization, the contacts in the latter circuit, however, being short-circuited by the test or private wiper 71 while passing over grounded busy contacts. As soon, therefore, as the test wiper 71 arrives at an ungrounded test contact the test relay 64 deenergizes and opens the rotary magnet circuit, thereby bringing the wipers to rest upon the terminals of an idle trunk line, assumed to be in this case the contacts 73, 74, and 75. As a further result of the deenergization of the test relay 64, a circuit is completed for the line switching relay 63 which relay, upon energizing, disconnects the extended line conductors 12 and 11 from the windings of the line relay 60 and further extends them by way of wipers 70 and 72, bank contacts 73 and 75, and conductors 80 and 82 to the line relays 100 and 101 of the repeater R. The line relays 100 and 101 are accordingly energized over the calling subscriber's loop. Relay 101, upon attracting its armature, closes a circuit for slow-acting relay 102 as follows: ground at G¹⁰, circuit springs 110 and 111, and winding of relay 102 to battery B. Upon energizing relay 102 completes a holding circuit for the selector E and line switch C which may be traced as follows: ground at G¹¹, circuit springs 115 and 116, conductor 81, bank contact 74, and wiper 71 to wire junction 92, where the circuit divides, one branch extending by way of normally closed circuit springs of relay 64 and the winding of line switching relay 63 to battery B, and the other branch extending by way of off-normal contact 93, and in

terrupter contact 95 to wire junction 94 where it joins the previously traced holding circuit extending back to line switch C. It is understood, of course, that the new holding circuit is completed before the deenergization of slow-acting relay 61.

Returning to the repeater R, as a further result of the energization of relay 102 a circuit is prepared for relay 103 by the closure of contact springs 119 and 120, and in addition a circuit is completed for the double-wound line relay 160 of the selector F which may be traced as follows: ground at G¹⁴, lower winding of relay 160, contact springs 96 and 97, conductor 84, contact springs 113 and 114, contact springs 118 and 117, contact springs 124 and 125, winding of impedance coil 105, contact springs 121 and 122, conductor 83, contact springs 99 and 98, and upper winding of relay 160 to battery B'. Upon attracting its armature, the line relay 160 closes an energizing circuit for the slow-acting relay 161 which relay upon energizing, prepares circuits for the vertical and rotary magnets of the selector F in the usual manner.

Having disposed of the circuits controlled by the line relay 101 of the repeater we will now consider the line relay 100. Upon the energization of this latter relay a charging circuit for the condenser 106 is closed over the following path: ground at G¹², contact springs 107 and 108 and condenser 106 to battery B. The condenser 106 is therefore at once charged to the potential of the battery B. The contact springs 109 and 107 of relay 100 are preferably so adjusted that at about the middle of the armature's stroke the contact spring 108 will leave contact spring 109 and at the same time or an instant later will come into engagement with contact spring 107.

The calling subscriber may now proceed to dial the second digit of the desired number, resulting as before in interruptions of his loop to which the line relays 100 and 101 are now responsive by retracting their armatures a corresponding number of times. At the first deenergization of relay 101 a circuit is completed for the slow-acting relay 103 as follows: ground at G¹⁰, contact springs 110 and 112, contact springs 120 and 119, and winding of relay 103 to battery B. Relays 102 and 103, being slow-acting, retain their armatures in operated position during a series of deenergizations of relay 101, after which relay 103 retracts its armature. In its energized condition relay 103 disconnects the conductors 83 and 84 from the conductors 80 and 82, respectively, and from the normally bridged impedance coil 105; and substitutes for the latter a direct path by way of contact springs 123 and 124, contact springs 117 and 118, and contact springs 114 and 113.

- At each deenergization of the line relay 100 the left hand terminal of the condenser 106 is connected to the lower terminal of relay 104 by way of contact springs 108 and 109. The condenser 106 is therefore discharged through the winding of relay 104 and as a result of the discharging current the relay 104 is operated momentarily to separate its contact springs 113 and 114.
- 10 Since the condenser 106 receives a new charge at each energization of the line relay 100, it follows that the relay 104 will be operated at each deenergization of the said line relay to repeat the interruptions of the 15 subscriber's loop into the previously described energizing circuit of the line relay 160 of the selector F.
- In response to these interruptions of its circuit the line relay 160 operates to control 20 the selector F in precisely the same manner as was described in the case of the selector E, whereby the wipers 170, 171, and 175 are raised step by step until they stand opposite the proper horizontal level of bank contacts,
- 25 after which they are automatically rotated until they arrive at contacts, assumed in this case to be the contacts 173, 174, and 175, which are terminals of an idle trunk line. The wipers having been brought to rest upon 30 the contacts of an idle trunk line, the line switching relay 163 is energized to disconnect the line conductors 83 and 84 from the line relay 160 and extend them instead by way of wipers 170 and 172, bank contacts 35 173 and 175 to the double-wound line relay 200 of the connector H. Upon attracting its armature, the line relay 200 closes an energizing circuit for the slow-acting relay 201 which relay, upon energizing in turn, completes a holding circuit from ground G¹⁶ for 40 the line switching relay 163 of the selector F in the usual manner.
- The calling subscriber may now manipulate his calling device in accordance with 45 the third digit of the desired number, thereby causing another series of deenergizations of the line relays 100 and 101 of the repeater R. As before the relay 104 will be operated by successive discharges from the condenser 50 106 to produce a series of interruptions in the circuit of the line relay 200 of the connector H. Responsive to these interruptions the line relay 200 deenergizes a corresponding number of times and sends each time an impulse from ground at G¹⁷ to the slow-acting relay 207 and the vertical magnet 204 in series, side switch wiper 215 being in its 55 first position. The vertical magnet, in response to these impulses, steps up the shaft 60 until the wipers 220, 221, and 222 stand opposite the horizontal level of bank contacts in which the line of substation A' terminates. Relay 207, being slow-acting, retains its armature during the series of impulses and maintains a circuit from ground 65 at G¹⁸ for the private magnet 208 and the wiper cut-off relay 211 in parallel. At the end of the series of impulses, the relay 207 deenergizes and breaks the circuit of the private magnet, which latter controls the 70 side switch wipers in the usual manner to advance them to their second position.
- The subscriber at substation A may now operate his dial in accordance with the 75 fourth and final digit of the desired number, resulting as before in deenergizations of the line relay 200. Now, however, side switch wiper 215 being in its second position, the line relay sends impulses to the slow-acting relay 207 in series with the rotary magnet 205. The rotary magnet operates in response to these impulses to rotate the wipers 220, 221, and 222 until they rest, 80 respectively, upon bank contacts 223, 224, and 225, these contacts forming the terminal of the line of substation A' in the bank of connector H. The private magnet 208 and the wiper cutoff relay 211 are energized during this series of impulses as before, the latter disconnecting the line wipers during 85 rotation and the former, upon deenergizing, controlling the side switch wipers to advance them to their third position, it being assumed that the line of substation A' was 90 idle when called.
- 95 As side switch wiper 214 comes into engagement with its third position contact point, a circuit is completed for the cut-off winding 18' of line switch C' as follows: ground at G¹⁹, side switch wiper 214 (in third position), wiper 221, bank contact 224, and winding 18' to battery B'. By the closure of the above circuit the cut-off armature 22' is operated to disconnect the line conductors 11' and 12', respectively, from ground and from the line relay 16'. Ground at G¹⁹ also extends to multiples of bank contact 224 in the banks of other connectors of the group, thereby making the 100 line of substations A' busy to other calls.
- 105 By the engagement of side wipers 212 and 213 with their third position contact points the connection between the calling and called substations is completed, relay 211 being deenergized. By the engagement of side switch wiper 215 with its third position contact point, a circuit is completed for the ringing relay 209 in series with the interrupter I, whereby ringing current is projected intermittently out over the line of 110 substation A' to operate the signal in bridge thereof.
- 115 The subscriber at substation A has now established the required connection with substation A' and the bell at the latter substation is being rung to attract the attention of the called subscriber. When the called subscriber removes his receiver from the hook a circuit is completed for the double-wound back bridge relay 202 in the well 120
- 125 130

known manner. Upon attracting its armature, relay 202 closes a circuit for the ring cut-off relay 210 which relay locks itself to ground at G^{19} and also opens the circuit of the ringing relay 209, thereby stopping the ringing operation. As a further result of the energization of relay 202 the incoming line conductors are reversed as regards their connection with the winding of line relay 200. The latter operation is without importance in the system shown here, although it is provided in case it is desired to operate meters or similar apparatus.

The calling and called subscribers may now converse without further effort. Current for the transmitter at substation A is supplied through the windings of the line relays 100 and 101 of the repeater R, while current for the transmitter at substation A' is supplied through the windings of the back bridge relay 202. The voice currents follow the path shown in the heavy lines which, it is thought, will be apparent without further amplifying the explanation.

When the conversation is completed both subscribers will hang up their receivers. By the replacement of the receiver at substation A the circuit of the line relays 100 and 101 of the repeater R is broken. Upon deenergizing, relay 100 operates relay 104 again momentarily to transmit another impulse to the connector H but this impulse is of no particular consequence. By the deenergization of relay 101 the circuit of slow-acting relay 102 is broken. Upon deenergizing, relay 102 removes ground G^{11} from the holding circuit extending back to the selector E and the line switch C, whereupon these switches will restore to normal in the usual and well known manner. As a further result of the deenergization of relay 102 the energizing circuit for the line relay 200 of the connector H is broken at contact springs 117 and 118. The line relay 200 is accordingly deenergized and causes the deenergization of relay 201. By the latter operation ground G^{16} is removed from the holding circuit of the selector F and a circuit is closed for the release magnet 203 of the connector H, whereby these switches are also restored to normal.

The operation of a connector switch such as the connector H when connection is attempted with a busy line is well known and has been fully described in the publications previously mentioned. Since my invention involves nothing new in connection with this feature of the operation the description thereof will be omitted.

Considering now more in detail the manner in which impulses are standardized at the repeater R, the operation depends upon the fact that at each deenergization of the line relay 100 a uniform current is delivered to the relay 104 from the condenser 106.

That this is true will be evident when it is considered that a condenser, when connected directly across the terminals of a battery, will be charged instantly to nearly the full potential of the battery even though an infinite time is required theoretically for it to attain its full charge. It makes practically no difference therefore in the amount of charge received by the condenser how long the contact springs 107 and 108 remain together on successive energizations of the line relay. The condenser receives nearly a full charge within a very small fraction of a second after these springs make contact and their continued engagement can increase this charge but little. The relative values of the capacity of the condenser 106 and the resistance of the relay 104 are of importance in the practical operation of the device for these factors determine the time required for each discharge of the condenser and therefore to a certain extent the length of the impulses delivered. I have found in tests that a condenser with a capacity of 5 microfarads and a relay with a resistance of 1000 ohms give good results.

Referring now to Fig. 4, the repeater R' is exactly the same as repeater R except for the circuit of the condenser 106' and the relay 104'. In the circuit, Fig. 4, the condenser 106' is short-circuited and therefore discharged at each energization of the line relay 100', while at each deenergization of the line relay 100' the condenser 106' is charged in series with the relay 104'. This is just the reverse of the operations which take place in the case of repeater R but the result is the same, for the condenser is for all practical purposes completely discharged each time, and receives each time a charge which is to a great extent independent of the length of the contact between the springs 108' and 109'. The modification shown in Fig. 4 is rather an obvious one but it has been thought best to show the circuit.

Other modifications can doubtless be made to adapt the invention to other types of automatic telephone systems or even to other uses altogether, and I do not, therefore, wish to limit the scope of the invention to the precise circuits shown. What I consider to be new and desire to have protected by Letters Patent will be pointed out in the appended claims.

What I claim as my invention is:

1. In an automatic telephone system, the combination with a circuit controlling relay, of a condenser, and a second relay for charging and discharging said condenser to thereby operate said controlling relay, the path for discharging currents including said controlling relay, and conductive paths from the opposite sides thereof to the opposite sides of the said condenser.

2. In an automatic telephone system, a

- circuit controlling relay, a condenser, a charging circuit for said condenser including a source of current, a continuous conductive discharging circuit for said condenser including said controlling relay, and a second relay for controlling said circuits to thereby operate said controlling relay.
3. In an automatic telephone system, a device for repeating impulses, said device comprising an impulse sending relay, a condenser, and a second relay provided with means for operating said first relay through the medium of said condenser.
4. In combination, a circuit, a controlling relay therefor, a condenser, a second relay and an energizing circuit therefor, a charging circuit for said condenser closed by said second relay when energized, and a discharging circuit for said condenser closed by said second relay when deenergized.
5. In combination, a first circuit, a second circuit, a relay bridge across the first circuit, a condenser, means for closing said first circuit to operate said relay bridge, means controlled thereby for charging said condenser and for closing said second circuit, a relay for opening said second circuit, and means for interrupting said first circuit, said relay bridge responsive to such interruption for discharging said condenser through said second relay.
6. In combination, a first circuit, a second circuit, means responsive to the closure of the first circuit for closing said second circuit, a relay for transmitting impulses over the second circuit, a condenser, a relay controlled by impulses received over the first circuit for charging and discharging said condenser, and a circuit for the discharging currents through said first relay.
7. In a telephone system, a trunk line divided into two sections, the second section terminating in an automatic switch, and an impulse repeater joining the two sections of said trunk line, said repeater comprising a relay controlling the continuity of the second section, and a second relay controlled over the first section and adapted to control said first relay through the medium of a condenser.
8. In a telephone system, a trunk line divided into two sections, the second section terminating in an automatic switch, and a repeater joining the two sections of said trunk line, said repeater comprising an impulse sending relay for controlling said switch, a condenser, and a second relay controlled by each impulse received over the first section to charge said condenser and discharge it through said first relay.
9. In a telephone system, a trunk line divided into two sections, the second section terminating in an automatic switch, and an impulse repeater joining the two sections of said trunk line, said repeater comprising an impulse sending relay for controlling said switch via the second section of said trunk line, and a second relay responsive to impulses received over the first section of said trunk line for controlling said first relay through the medium of a condenser.
10. In a telephone system, a trunk line divided into two sections, the second section terminating in an automatic switch, and a repeater provided with means for transmitting impulses from one section to the other, said means comprising a condenser, a relay controlled over the first section for charging and discharging said condenser at every impulse, and a second relay in series with said condenser for repeating said impulses into the second section.
11. In a telephone system, a trunk line divided into two sections, the second section terminating in an automatic switch, and a repeater provided with means for transmitting impulses from one section to the other, said means comprising a condenser, a relay controlled over the first section for charging and discharging said condenser at every impulse, and a second relay controlled by the discharge current from said condenser for repeating said impulses into the second section.
12. In combination, an impulse controlled switching device and a controlling circuit therefor, a second circuit, means for producing operating impulses in said second circuit, and a device for repeating impulses from the second circuit into said controlling circuit, said device comprising an impulse sending relay associated with said controlling circuit, and a relay in said second circuit responsive to impulses therein for controlling said first relay through the medium of a condenser.
13. In combination, an impulse controlled switching device and a controlling circuit therefor, a second circuit, means for producing operating impulses in said second circuit, and a device for repeating impulses from the second circuit into said controlling circuit, said device comprising an impulse sending relay associated with said controlling circuit, a condenser, and a relay in said second circuit responsive to each impulse therein to charge said condenser and discharge it through said first relay.
14. In an automatic telephone system, an automatic impulse correcting repeater, said repeater comprising an impulse sending relay, a condenser, a relay responsive to received impulses for alternately charging and discharging said condenser, and circuit so arranged that upon each discharge of said condenser the said impulse sending relay is operated by current stored in the said condenser during the previous charge.
15. In a telephone system, a device for simultaneously repeating and standardiz-

- ing electrical impulses, said device comprising an impulse receiving relay, an impulse transmitting relay, a condenser, a battery, and circuits controlled by said impulse receiving relay whereby said condenser is alternately charged from said battery and discharged through said impulse transmitting relay to operate the same.
16. In a telephone system, an electrical impulse correcting repeater, comprising an impulse receiving relay, an impulse transmitting relay, and circuits including a battery and a condenser whereby the latter relay is operated by the former by current stored in said condenser.
17. The combination with a relay and a battery, of a conductor joining one pole of said battery to one terminal of said relay, a condenser having one terminal connected to said conductor, a switch for connecting the other terminal of said condenser alternately to the other terminal of said relay and the other pole of said battery, and an armature for said relay operated by discharge currents from said condenser.
18. The combination with a condenser, of a circuit therefor having two branches, a magnet in one branch, a battery in the other branch, means for closing said branches alternately, and an armature for said magnet operated upon the closure of the associated branch.
19. The combination with a relay and a condenser, of means for repeatedly discharging said condenser through said relay to operate the same, and means for charging said condenser between successive discharges thereof.
20. The combination with two circuits containing respectively a battery and an electromagnet, of a condenser, and suitable means for connecting said condenser in said circuits in alternation, whereby electrical energy may be transferred from the battery circuit to the other circuit to operate the magnet included therein.
21. The combination with a source of electrical energy and a receiving circuit including an electromagnetically operated device, of a condenser, and suitable means for alternately charging said condenser from said source and discharging it into said circuit to operate the said device.
22. The combination with a battery and a magnet, of a condenser and a circuit therefor, and means for completing said circuit alternately through said battery and said magnet to operate the latter by means of current stored in said condenser.
23. The combination, with a first circuit and a second circuit, of a repeater comprising a condenser, a relay in said first circuit responsive to impulses received thereover to alternately charge and discharge said condenser, and a repeating relay in the discharging circuit for producing impulses in said second circuit, the said repeater constituting means for correcting irregularities in the received impulses, whereby a series of irregular or excessively long or short impulses is translated into a series of uniform impulses of standard length.

Signed by me at Chicago, Cook county, State of Illinois, this 4th day of August, 1916.

RODNEY G. RICHARDSON.
